DESIGN FOR A COAT

Philip Graber, New York, N. Y.

Application July 24, 1944, Serial No. 114,525

Term of patent 3½ years

(Cl. D3—4)

To all whom it may concern:

Be it known that I, Philip Graber, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my design;

Fig. 2 is the rear view of the coat shown in Fig. 1, and

Fig. 3 is a fragmentary view of Fig. 1 illustrating the adjustable fur tuxedo revers with one side thereof folded under.

The characteristic features of my design reside in the portions shown on the drawing in heavy lines.

I claim:

The ornamental design for a coat, substantially as shown and described.

PHILIP GRABER.
